[57] CLAIM

The ornamental design for a pom-pom maker or the like, substantially as shown and described.

DESCRIPTION

FIG. 1 is a front elevational view of a pom-pom maker or the like showing my new design, the opposite side being identical thereto;

FIG. 2 is a bottom plan view thereof;

FIG. 3 is a top plan view thereof;

FIG. 4 is a right side elevational view thereof, the opposite side being identical thereto.
